UNITED STATES PATENT OFFICE.

CHRISTIAN BODMER AND STUART W. PARSONS, OF NEW BRITAIN, CONNECTICUT, ASSIGNEES TO THE STANLEY WORKS, OF NEW BRITAIN, CONNECTICUT, A CORPORATION OF CONNECTICUT.

JOINT FOR TOOLS AND THE LIKE.

Application filed May 9, 1924. Serial No. 712,045.

To all whom it may concern:

Be it known that we, CHRISTIAN BODMER and STUART W. PARSONS, citizens of the United States, and residents of New Britain, county of Hartford, State of Connecticut, have invented certain new and useful Improvements in Joints for Tools and the like, of which the following is a specification.

This invention relates, generally, to tools and the like of the sort having a body portion with a slot or groove, and a relatively thin blade or tongue fitting within the slot of the body portion and immovably secured thereto. As an instance of an application of the present invention, reference may be had to a square, such as is illustrated in the drawing, and having a handle or body portion with a relatively narrow, deep slot at one end and a blade fitting within the slot and secured in place as hereinafter described.

The aim of the present invention is to provide an improved union or connection between the body portion and blade, the connection being characterized by its simplicity, its strength and durability, by its neatness in appearance, and the ease and economy with which it may be made.

Other objects will be in part obvious and in part pointed out more in detail herein-after.

The invention accordingly consists in the features of construction, combination of elements and arrangement of parts which will be exemplified in the construction herein-after set forth, and the scope of the application of which will be indicated in the appended claims.

In the accompanying drawing, wherein I have shown, for illustrative purposes, one embodiment which the present invention may take, it being understood that this showing is by way of exemplification only and that the invention is susceptible of various modifications and changes,

Figure 1 is a side elevation of a try square;

Fig. 2 is a perspective view showing the blade and handle before they are assembled together;

Fig. 3 is a sectional view through the handle before the blade is secured thereto, this view being substantially on line 3-3 of Fig. 2; and

Fig. 4 is a sectional view taken on line

4-4 of Fig. 1 and showing the union between the blade and handle.

Referring to the drawing in detail, *a* designates a body portion which, in the present instance, is in the form of a handle or beam, and *b* designates a relatively thin tongue which is in the form of a blade. The handle *a* is provided, at one end, with a relatively deep, narrow slot 10 in which closely fits one end of the blade *b*, as is usual in structures of this sort.

In accordance with the present invention, the handle *a*, at its slotted end and on each side, is provided with a raised portion, boss or button 11 with which the welding terminals of a spot welding fixture or machine 70 are adapted to contact during the welding operation, and the blade *b* is provided with an aperture or hole 12 adapted to register with the bosses 11 when the blade is properly inserted in the slot 10. About each of the 75 bosses 11 may be provided an annular rib 13 which serve, in a measure, to absorb the heat generated during the welding operation and thus prevent discoloration of the handle beyond these ribs. These ribs also serve 80 the purpose of preventing the molten metal from spreading to any great extent and marring the appearance of the tool.

After the parts are constructed as described, the blade is inserted in the slot 85 10 with the hole 12 in alinement with the centers of the bosses 11. The opposing terminals of a spot welding machine are then brought into engagement with the bosses and, as the current passes between the terminals, the bosses are fused and the fused metal will run into the hole 12 and thus form, so to speak, a rivet integral with the handle and extending through the blade. During the welding operation, the handle 95 and blade are fused together so that a very secure joint is obtained and the parts are held tightly together against relative movement. As stated, the annular ribs take up the heat which would otherwise spread, 100 and thus discoloration and marring of the handle beyond these ribs is effectively guarded against. Also, these ribs form pockets into which the metal of the bosses, as they are melted down, runs, thus confining the extent of spread of the fused metal.

From the foregoing description, it will

be seen that the process employed for connecting the parts together may be very easily and economically carried out, so that the cost of the device is materially reduced. 5 and a very secure, tight union is obtained.

As many changes could be made in the above construction and many apparently widely different embodiments of this invention could be made without departing

10 from the scope thereof, it is intended that all matter contained in the above description or shown in the accompanying drawing shall be interpreted as illustrative and not in a limiting sense.

15 It is also to be understood that the language used in the following claims is intended to cover all of the generic and specific features of the invention herein described and all statements of the scope of 20 the invention which, as a matter of language, might be said to fall therebetween.

We claim, as our invention:

1. A square having a handle portion provided at one end with a relatively deep, 25 narrow slot, a boss on each side of the handle at the slotted end thereof and a rib about each boss; and a blade fitting in said slot and having a hole in alignment with the bosses, said bosses being fused to form 30 an integral rivet extending through said hole and united with said blade.

2. The herein described method which

consists in forming a body portion with a slot and a tongue with a hole, positioning the apertured portion of the tongue in the 35 slot of the body portion, and fusing the metal of the body portion adjacent the hole to form an integral rivet extending through the hole and to unite together the metal of the tongue and body portion adjacent 40 the hole.

3. The herein described method which consists in forming a body portion with a slot and a boss on each side, forming a tongue with a hole, positioning the aper- 45 tured portion of the tongue in said slot, and passing an electric current through the bosses to fuse the same and form an integral rivet extending through the hole.

4. The herein described method which 50 consists in forming a body portion with a slot, a boss on each side and an annular rib about each boss; forming a tongue with a hole; positioning the tongue in the slot with the hole in alignment with the bosses, 55 and electrically welding the parts together by passing a current through the bosses, thereby fusing the same with the tongue and forming a rivet integral with the body portion and extending through the hole in 60 the tongue.

CHRISTIAN BODMER.
STUART W. PARSONS.
